No. 628,196.

Patented July 4, 1899.

E. M. CUNARD & C. C. HANNOLD.
FOLDING BOX.

(Application filed Apr. 29, 1898.)

(No Model.)

FIG. I.

UNITED STATES PATENT OFFICE.

ELBERT M. CUNARD, OF WESTVILLE, AND CHALKLEY C. HANNOLD, OF WOODBURY, NEW JERSEY.

FOLDING BOX.

SPECIFICATION forming part of Letters Patent No. 628,196, dated July 4, 1899.

Application filed April 29, 1899. Serial No. 715,014. (No model.)

To all whom it may concern:

Be it known that we, ELBERT M. CUNARD, a resident of Westville, and CHALKLEY C. HANNOLD, a resident of Woodbury, in the 5 county of Gloucester and State of New Jersey, citizens of the United States, have invented certain new and useful Improvements in Folding Boxes, of which the following is a specification.

10 Our invention relates particularly to those folding boxes which are generally constructed of sheet metal and which are also adapted to be folded into small compass, so as to be placed and carried in a garment-pocket of ordinary size, or which can be readily unfolded and set 15 up to provide a rigid box in which food or other articles may be placed and protected from injury or the liability of being crushed while being carried; but our invention is well 20 adapted for large boxes, as well as boxes of ordinary size.

In order that our invention may be fully understood, we will proceed to describe it with reference to the accompanying drawings, in 25 which—

Figure I is a perspective view of our improved folding box. Fig. II is an edge view of the box after it is folded, the body being located within the cover and concealed there- 30 by. Fig. III is a perspective view of the body of the box, showing it in course of being set up, the arrows shown in connection therewith indicating the direction in which the parts are moved when it is desired to fold the 35 body. Fig. IV is an inside view of the body when laid out. Fig. V is an edge view of the body after it is folded ready to be placed within its cover. Fig. VI is a detail view of a handle-loop, showing a modification.

40 In carrying out our invention we construct the body of our box of eight approximately square pieces of any kind of suitable sheet material, such as sheet metal.

1 are the two bottom pieces of the body, 45 each bottom piece being formed with an out-turned lip-flange 1^a at its inner edges, with an inturned lip-flange 1^b at one side, and with an upturned lip-flange 1^c at the other side. The side lip-flange 1^b and the lap-flange 1^c of one 50 bottom piece are located at opposite sides to

the side lip-flange 1^b and the lap-flange 1^c of the other bottom piece.

Each side of the body consists of two pieces 2 3, one side piece 2 being formed with an out-turned lip-flange 2^a at its vertical inner edge 55 and with an inturned lip-flange 2^b at its vertical outer edge, and the other side piece 3 being formed with an out-turned lip-flange 3^a at its vertical inner edge, with an inturned lip-flange 3^b at its lower edge, and with a 60 half inturned lap-flange 3^c at the lower part of its vertical outer edge. The two similar pieces 2 of the sides are located opposite the other two similar pieces 3 of the sides.

4 are the two end pieces of the body, each 65 formed with an inturned lip-flange 4^a at its vertical inner edge, with an inturned lap-flange 4^b at its lower edge, and with an in-turned half lap-flange 4^c at the upper part of its vertical outer edge. The adjacent lip- 70 flanges of the body-pieces are hinged together by pins 5.

6 are two pieces which provide a cover for the body of the box and are each formed with downturned lap-flanges 6^a at the sides, hav- 75 ing overlapping ears 6^b , and with a down-turned lap-flange 6^c at the outer end. The ears 6^b of the cover are hinged together by headed pivots 7, so as to adapt the two parts of the cover to be folded together and occupy 80 the space of one part of the cover, while the chamber formed therein provides a receptacle for the body of the box when folded.

The end pieces 4 are provided with tongue-pieces 8, pivoted thereto by fastenings 9, so 85 as to occupy one position (shown in Figs. I and III) or to be turned in the opposite position out of the way, as shown in dotted lines in Fig. IV, when the body is folded. Each piece 6 of the cover is provided with a trans- 90 verse loop 10, secured by rivet-fastenings 11, as shown in Fig. I, or by passing the ends of the loops through slots 11^a and bending them against the inside of the cover, as shown in Fig. VI, and through these loops the end of 95 a strap 12 extends. This strap is provided at its ends with buckles 13, with which the tongue-pieces 8 are adapted to be engaged. Secured to the strap 12 is a carrying-handle or handhold 14. It will thus be understood 100

that the bottom pieces are hinged together, that the flanged sides 3 are hinged to their respective bottom pieces, that the end pieces 4 are hinged to the other side pieces 2, which 5 in turn are hinged to the flanged side pieces 3.

To set up the body, it is opened on the bottom hinge, the end pieces 4 and side pieces 2 and 3 are turned upward from the bottom pieces 1, the end pieces 4 are turned outward 10 on the adjacent side pieces 2, and the end pieces 4 and side pieces 2 are swung around away from the side pieces 3, and the bottom pieces 1 are partly folded downward, so that the parts assume the positions shown in Fig.

15 III. The lower edges of the side pieces 2 are passed inside of the upturned lap-flanges 1^c of the bottom pieces 1, and the bottom pieces 1 are straightened out. The end pieces 4 are brought into position so that their inturned 20 lap-flanges 4^b extend beneath the bottom pieces 1 to support the latter, and their outer vertical edges are tucked within the half lap-flanges 3^c of the side pieces 3, and the half lap-flanges 4^c of the ends extend outside the 25 outer edges of the side pieces 3, thus interlocking the ends with the bottom and sides of the body. The cover-pieces 6, being straightened out, can next be placed on the body. The tongues 8 on the end pieces are 30 turned to vertical position and engaged with the strap-buckles 13 to secure the cover. To fold the body, the tongues are unbuckled and turned downward, the cover removed, the ends detached and folded inward on the side 35 pieces 2, and the side pieces 2, with the ends, are folded on the side pieces 3, and the ends and side pieces are folded on their respective bottom pieces and the bottom pieces folded together. The body is next placed in the 40 inner part of the cover and the outer part of the cover folded thereover, so that the folded body is entirely concealed.

The lap-flanges 4^b on the lower edges of the end pieces are adapted to support the ends 45 of the bottom pieces when the lap-flanges 4^c of the end pieces 4 are passed over the lap-flanges 3^c of the side pieces 3.

Having thus described our invention, the following is what we claim as new therein and desire to secure by Letters Patent:

50

1. A folding-box body comprising the bottom pieces hinged together, the sides each side consisting of two pieces hinged together, one piece of each side being formed with an inturned lap-flange at its vertical outer edge, 55 and hinged to a bottom piece, and the end pieces each end piece being formed with an inturned bottom lap-flange and an inturned lap-flange at its vertical outer edge and hinged to one of the other side pieces; substantially 60 as described.

2. A folding-box body comprising the bottom pieces hinged together, each of the bottom pieces having an upturned lap-flange, the sides, each side consisting of two pieces 65 hinged together, one piece of each side being formed with an inturned lap-flange at its vertical outer edge, and hinged to a bottom piece, and the end pieces, each end piece being formed with an inturned bottom lap-flange 70 and an inturned lap-flange at its vertical outer edge and hinged to one of the other side pieces; substantially as described.

3. A folding box comprising a body having bottom pieces hinged together, the sides; each 75 side consisting of two pieces hinged together, one piece of each side being formed with an inturned lap-flange at its vertical outer edge, and hinged to a bottom piece, and the end pieces; each end piece being formed with an 80 inturned bottom lap-flange and an inturned lap-flange at its vertical outer edge and hinged to one of the other side pieces, and the cover consisting of two pieces having downturned lap-flanges at their sides formed with ears 85 hinged together and with downturned lap-flanges at their ends; substantially as described.
